ATTORNEYS

UNITED STATES PATENT OFFICE.

DOZIER FINLEY, OF BERKELEY, CALIFORNIA, ASSIGNOR TO THE PARAFFINE COMPANIES, INC., OF SAN FRANCISCO, CALIFORNIA, A CORPORATION OF DELAWARE.

ROOFING.

Application filed December 21, 1922. Serial No. 603,141.

To all whom it may concern:

Be it known that I, DOZIER FINLEY, a citizen of the United States of America, and a resident of Berkeley, county of Alameda, 5 and State of California, have invented a new and useful Roofing, of which the following is a specification.

My invention relates to prepared roofings and one of the objects of the invention is 10 the provision of a prepared roofing of which the entire surface is covered with a granular material, a portion of such granular material being of a different color than the rest and disposed in a straight line spaced from and 15 parallel to one edge of the roofing so that it may act as a guide line in the spacing of the lap when the roofing is laid.

My invention possesses other objects and 20 features of advantage, some of which, with the foregoing, will be set forth in the following description of the invention. It is to be understood that I do not limit myself to the showing made by the said description as I may adopt variant forms of my invention 25 within the scope of the claims.

Referring to the drawings: Fig. 1 is a plan view of a section of my roofing and Fig. 2 is a sectional view thru the roofing taken on the line 2—2 of Fig. 1.

30 My roofing comprises a felt base sheet 2 impregnated and coated with a bituminous material in the usual or any desired manner. While the coated surface of the sheet is still in an adhesive condition, a surfacing or coating of granular material is applied there-over so that it is embedded in and held by 35 the bituminous coating. Such surfacing preferably consists of three parts, one of which is a marginal strip 3, which may be about two inches wide and which extends 40 along one edge of the sheet. The material for this portion of the coating is quite fine preferably of a size to pass thru a 35-mesh screen. Bordering the marginal strip on 45 the inside is a narrow strip of preferably a white sand 4, which may be about one-quarter of an inch wide, and substantially parallel to the edge of the sheet. The remainder of the surface of the sheet is covered 50 by a coarser granulated material 5 which is preferably of the same material as that forming the strip 3.

In crushing the material for the coating 5 considerable quantities of the finer sizes are 55 formed and these are preferably used for

the marginal strip, thus providing a use for a material otherwise wasted. Such material may be of any suitable nature, such as crushed slate, or crushed brick. It is desirable however, that the narrow strip 4 60 shall be a different color than the bordering areas, so that it stands out from the surface in a clearly marked line, which becomes particularly useful in indicating the correct amount of lap when the roofing sheets are 65 laid.

I am aware that roofings have heretofore been made with a marginal strip of sand. My invention, however, has marked advantages over such prior roofings in that the 70 quantity of sand used in a narrow line is materially less than for a comparatively wide surface, so that the amount of it which becomes mixed with the adjoining granular coating is negligible, thus preserving the 75 color of the adjoining coating. By using on the marginal strip, the fines of the same material with which the major portion of the sheet is coated, an otherwise waste product is put to good use with a consequent 80 saving in cost of production. A superior surface is provided by the finely granulated material upon which a weather-tight lap may be formed.

It is of course obvious that any other 85 color scheme resulting from a choice of surfacing materials other than those named will be equally effective in providing a roofing of distinctive appearance and embodying the lap guide. 90

I claim:

1. A prepared roofing comprising a roofing sheet, a lap guide line of granular material disposed thereon, a surfacing of fine granular material on one side of said line, 95 and a surfacing of coarse granular material on the opposite side of said line, said lap guide line being of a different color from the fine and coarse granular material to thereby strikingly indicate the exact point 100 of overlap for the adjoining roofing sheet.

2. A prepared roofing comprising a roofing sheet, a lap guide line of granular material disposed thereon, and a surfacing of granular material of different color than the material of said guide line on each side of said line, that on one side being coarse and that on the other side being fine. 105

3. A prepared roofing comprising a roofing sheet, a narrow line of granular mate- 110

rial disposed thereon constituting a lap different material and color strikingly indicates the exact point of overlap for the ad-
guide of small width, and a surfacing of joining roofing sheet.
granular material of different color than 10
the material of said guide line on each side In testimony whereof, I have hereunto
5 of said line, that on one side being coarse set my hand.
and that on the other side being fine, where-
by the relatively narrow lap guide line of

DOZIER FINLEY.
